DESIGN FOR A GARMENT HANGER

Frank B. Kraus, New York, N. Y.

Application August 2, 1947, Serial No. 140,676

Term of patent 3½ years

(Cl. D33—8)

To all whom it may concern:

Be it known that I, Frank B. Kraus, a citizen of the United States, residing at New York, in the county and State of New York, have invented a new, original, and ornamental Design for a Garment Hanger, of which the following is a specification, reference being had to the accompanying drawing, forming part thereof.

Fig. 1 is a plan view of a garment hanger, showing my design; and

Figs. 2 and 3 are, respectively, a side elevation and a perspective view thereof.

I claim:

The ornamental design for a garment hanger, as shown.

FRANK B. KRAUS.
